CONTROL DEVICE

Frederick S. Williams, New York, N. Y., assignor,
by mesne assignments, to Vaco Products, Inc.,
a corporation of Delaware

Application November 27, 1934, Serial No. 754,999

5 Claims. (Cl. 74—99)

The present invention relates to control devices and more particularly to a novel and improved control device for carrying out different controlling movements of different members by 5 repeated movement of a single member.

Objects and advantages of the invention will be set forth in part hereinafter and in part will be obvious herefrom, or may be learned by practice with the invention, the same being realized 10 and attained by means of the instrumentalities and combinations pointed out in the appended 15 claims.

The invention consists in the novel parts, construction, arrangements, combinations and improvements herein shown and described.

The accompanying drawing, referred to herein and constituting a part hereof, illustrates one embodiment of the invention, and together with the description, serves to explain the principles of the 20 invention.

Of the drawing:

Figure 1 is a side elevation, partly in section, of a typical embodiment which is illustrative of the present invention;

25 Figure 2 is a section taken on the line 2—2 of Figure 1 and showing the parts in the same positions as in Figure 1; and

Figures 3 and 4 are similar sectional figures showing the parts in other relative positions.

30 The present invention has for its object the provision of a novel and improved control device particularly adapted to operate a plurality of elements in different manners. A further object of the invention is the provision of a control device 35 by which the repeated movement of a single member will effect different control of other members. Still another object of the invention is the provision of a control device having a movable operating member adapted to position another member in either of its alternative positions.

40 Referring now in detail to the illustrative embodiment of the invention as shown in the accompanying drawing, the invention is shown in a form suitable for foot operation. As embodied, 45 there is provided a frame member 10, to be rigidly secured to the flooring or some other rigid member, and comprising a C-shaped bar provided with aligned apertures 11 and 12, in one of which is positioned a bushing 13. A plunger 14 is mounted for reciprocation in the aperture 12 and bushing 13, and at its upper end is provided with a button 15 to be engaged by the operator's foot, while a spring 16 is coiled about the plunger 14 and is compressed between the lower reach of 50 frame 10 and a recessed sleeve 18 mounted on

and bolted to plunger 14, serving to urge the plunger and sleeve upwardly. The lower end of plunger 14 may be apertured, as at 17, to receive a link or other control connection.

5 Means are also provided which may be moved to and held in either of two alternative positions by movement of the plunger 14 for the control of other associated devices or mechanisms, so constructed that these means may be held in either of its positions, with the plunger in its upper position. As embodied, these means comprise an arm 20 mounted on and pinned to shaft 21 journaled in a bushing 22 supported in the frame 10. At its inner end shaft 21 is integrally connected with a heart-shaped plate 24 adapted to 15 be moved by reciprocation of plunger 14.

For shifting plate 24 from one position to its other position, plate 24 is provided with two short, spaced-apart pins 25 and 26 mounted one on either side of shaft 21, and is also provided with a 20 pin 27 positioned equidistant from and above pins 25 and 26. Sleeve 18 is recessed on its side adjacent to plate 24 so as to receive an oscillatable dog 29 pivotally mounted on the bolt 30 by which sleeve 18 is secured to plunger 14. On its lower 25 face, dog 29 is provided with anvil faces 31 and 32 to engage pins 25 and 26 respectively as plunger 14 is reciprocated, and is also provided with shoulders 34 and 35 to be alternately engaged by pin 27 on the return stroke of plunger 14. On its 30 lower face, dog 29 is also provided with recesses 36 which engage with a ball 37 pressed upwardly into one or the other of the recesses to hold the dog in one or the other of two definite positions. The lower edge of the recess in sleeve 18 is bevelled to engage faces 31 and 32 to limit movement 35 of the dog 29.

A stop 40 is mounted on the inner face of frame 10 and projects into the cut-away recess at the bottom of plate 24 to limit oscillation of the plate. 40

In the operation of the embodiment described and illustrated, the successive positions of the parts are shown in Figures 2, 3 and 4. In Figure 2, the parts are in their normal position. As plunger 14 is moved down by pressure of the 45 operator's foot, dog 29 moves with it and face 32 engages pin 26 so that on completion of the downward stroke of the plunger, plate 24 has been shifted to its other position as shown in Figure 3, pin 27 clearing the top of the depressed 50 dog 29, and thereby moving arm 20 and the device controlled thereby.

When the operator releases his foot from the button 15, spring 16 returns plunger 14 to its upper position passing through the position 55

shown in Fig. 4. As there shown, pin 27 engages shoulder 35 and further upward travel of the plunger 14 serves to shift dog 29 to its other position, with anvil face 31 ready to engage pin 25 5 on the next stroke of plunger 14. In its normal position, pin 27 cooperates with the dog 29 to lock plate 24 in the position to which it has been moved.

On the next complete reciprocation of plunger 10 14, the parts will be restored to their original position as shown in Figure 2.

Repeated movement of the plunger 14 thus serves to give two positions of arm 20 and if the plunger 14 is also directly connected to a controlled device, there are four possible alternative 15 positions of the parts; that is, arm 20 may be in either of its positions with the plunger 14 either up or down.

The device as shown and described is capable 20 of wide use in connection with the control of various mechanisms and the invention in its broader aspects is not limited to the specific mechanisms shown and described but departures may be made therefrom within the scope of the 25 accompanying claims without departing from the principles of the invention and without sacrificing its chief advantages.

What I claim is:—

1. A control device including in combination 30 a plunger, a dog pivoted on the plunger, an oscillatable plate carrying an arm and having two alternative positions, spaced pins on the plate to be alternately engaged by the dog on its travel in one direction for swinging the plate and a 35 pin on the plate to engage alternate sides of the dog on the return movement of the plunger to swing the dog.

2. A control device including in combination 40 a plunger, a dog pivoted on the plunger, an oscillatable plate carrying an arm and having two alternative positions, spaced pins on the plate to

be alternately engaged by the dog on its travel in one direction for swinging the plate and a pin on the plate to engage alternate sides of the dog on the return movement of the plunger to swing the dog, said last pin also cooperating with the dog to lock the plate after return of the plunger. 5

3. A control device including in combination a plunger, a dog pivoted on the plunger, an oscillatable plate carrying an arm and having two alternative positions, spaced pins on the plate to be alternately engaged by the dog on its travel in one direction for swinging the plate, a pin on the plate to engage alternate sides of the dog on the return movement of the plunger to swing the dog, and means for holding the dog in 10 either of its positions. 15

4. A control device including in combination a plunger, a dog pivoted on the plunger, an oscillatable plate carrying an arm and having two alternative positions, spaced pins on the plate to be alternately engaged by the dog on its travel in one direction for swinging the plate, a pin on the plate to engage alternate sides of the dog on the return movement of the plunger to swing the dog, said last pin also cooperating with the dog to lock the plate after return of the plunger and means for holding the dog in either of its positions. 20 25

5. A control device including in combination a plunger, a dog pivoted on the plunger, an oscillatable plate carrying an arm and having two alternative positions, spaced pins on the plate to be alternately engaged by the dog on its travel in one direction for swinging the plate, a pin on the plate to engage alternate sides of the dog on the return movement of the plunger to swing the dog, said last pin also cooperating with the dog to lock the plate after return of the plunger, means for holding the dog in either of its positions, and a spring for returning the plunger. 30 35
